MACHINE FOR PACKING FLAT PACKETS
AND THE LIKEMichael Paridon, Barberton, Ohio, assignor to
The Diamond Match Company, New York,
N. Y., a corporation of Maryland

Application January 30, 1934, Serial No. 708,963

24 Claims. (Cl. 226—4)

This invention relates to a machine for packing flat packets, such as book or card matches, which machine is especially, though not exclusively, designed for use in connection with a book-match making machine embodying parallel delivery troughs along which the articles are advanced. In each of the troughs match books of tapering flat form are aligned in upright end position, face to face, with the large or head ends of adjacent books oppositely-disposed, that is to say, the end-wise positions of alternate books of the row are reversed as to the match heads. The principal object of my invention is to provide a machine whereby succeeding leading packets of two concurrently advancing rows are removed in a uniform and orderly manner and progressively assembled in two separate rows comprising each a predetermined number of packets, and whereby the two rows of packets thus assembled are arranged in close parallel relation and then packed in a commercial carton; the various mechanisms of the packing machine operating automatically and in timed relation to each other.

With this object in view, and others which will presently appear, the invention embodies features of construction and organization, and principles of operation, which will be hereinafter described; the scope of the invention then being expressed in the appended claims.

30 In the drawings—

Figure 1 is a side elevation of a packing machine embodying a form of my invention, the mechanisms being shown in their relative positions immediately upon the assembly of two separate rows of articles preparatory to their association.

Fig. 2 is an end elevation of the machine.

Fig. 3 is a horizontal section of the machine, as on the line 3—3 of Fig. 1.

40 Fig. 4 is a similar section, as on the line 4—4 of Fig. 1.

Fig. 5 is a longitudinal vertical section, as on the line 5—5 of Fig. 2.

Fig. 6 is a transverse vertical section of the machine, as on the line 6—6 of Fig. 1.

Fig. 7 is a transverse vertical section, as on the line 7—7 of Fig. 1, but showing the mechanisms in their relative positions during the packing of the associated rows of articles in a container.

50 Fig. 8 is a partial plan of a slotted bridge structure, including its assembly chambers, showing the article supply troughs at the respective sides of the structure, reciprocal ejectors for transferring the leading articles from the troughs to the respective chambers, pusher and backer

rods for the articles as they are progressively delivered to and aligned in the assembly chambers, and lifters for the rows of assembled articles.

Fig. 9 is a vertical section through the bridge structure and adjuncts, as on the line 9—9 of Fig. 8, but showing the lifters in their upward strokes advancing the opposing rows of articles to and upon the doors of the bridge throat, and also showing the presser members for aligning the rows in close parallel relation above the throat.

Fig. 10 is a perspective view of a match packet.

Fig. 11 is a plan of a commercial carton with match packets assembled therein in parallel rows.

The main supporting frame of the form of packing machine illustrated in the drawings comprises a base 20; spaced parallel standards 21 rising from the base, and spaced transverse cross-bars 22 for the standards. These standards have formed on their upper lateral portions outward extensions 23 upon which are respectively supported the outer ends of two spaced parallel discharge troughs 24 which may extend from a match-book machine or other source of book-match supply. The troughs support and guide in parallel rows the match books (or other packets) which are being progressively delivered to the receiving ends of the troughs, with the tapering flat backs of each row of books in upright end position, face to face, and with the large or head ends of adjacent books oppositely disposed, in order to ensure a uniform and compact assembly of the books.

Along the bottoms of the respective troughs are the upper runs of travelling endless chains 25 which receive the lower edges of the match books and frictionally advance the books through the troughs to the outer end walls 26 of the latter where predetermined numbers of the leading books are progressively separated from the respective rows in the troughs and positioned in assembly chambers, 27, at the sides of the packing machine.

A commercial book match carton, as commonly used, contains fifty books arranged in two adjacent equal rows, and therefore the present machine has been so designed that in each operating cycle thereof twenty-five of the reversely disposed books are transferred from each trough to the adjacent assembly chamber. To this end mechanism is provided whereby the leading books of each row are shifted in succeeding pairs from the trough into the adjacent assembling chamber until twenty-four books have been separated from the row and assembled, whereupon a single lead-

ing book of the row is pushed from the trough into the chamber to complete the count. The transfer mechanisms of the respective troughs are designed to effect the simultaneous transference 5 of match books from the troughs to the respective chambers. Each of the transfer mechanisms in a desired form includes a bifurcated ejector head 28 which is reciprocative horizontally through the adjacent trough, the walls of which 10 latter are vertically slotted, as at 29, to permit the free passage of the head. The head is affixed to an upstanding lug 30 on a horizontal slide 31 which is guided in ways 32 on an outwardly projecting shelf 33 whereof the flange 34 is fastened 15 on the extension of the adjacent frame standard. This shelf is slotted, as at 35, for the free passage of a depending roll 36 on the slide, which roll is operatively received by the race of a cam 37 fast on one end of a transverse shaft 38 extending 20 transversely of the machine and continuously driven in any suitable manner during the transference of the books to the assembly chambers.

The cam races for the respective slides are of corresponding form but in opposite relation, and 25 therefore during the rotation of the cams the slides are reciprocated in opposite directions to each other.

As herein illustrated the shaft 38 has its bearings in the frame standards and also in hubs 39 30 on the flanges 34 of the respective shelves. This shaft has fast thereon a bevel gear 40 in mesh with a similar gear 41 on the upper end of a vertical shaft 42 which has its bearings in a bracket 43 at one side of the main frame. Fast on the 35 lower end of the shaft 42 is a bevel gear 44 in mesh with a similar gear 45 loose on a longitudinally disposed drive shaft 46 having its bearings in one side of the main frame. The shaft 46 has fast thereon a pulley 47 which is connected 40 with and driven from a suitable source of power.

The bevel gear 45 is periodically connected to and released from the drive shaft by suitable clutch mechanism presently described. When such gear is clutched on the shaft 46 motion is 45 transmitted at corresponding speed from the latter to the transverse shaft 38 and its cams 37, and therefore the slides 31 together with their ejectors 28, are simultaneously reciprocated transversely of the respective troughs 24; it being noted that the contour of the races of the cams 50 37 is such that in one half rotation of the cams the slides are moved inward, and in the remaining half rotation they are retracted.

As herein illustrated the bevel gear 45 is backed 55 by a collar 48 fast on the drive shaft 46, and the hub on the opposite side of the gear is provided with a clutch member 49 in cooperative relation to a complementary clutch-member 50 on a sleeve 51 which is splined on the shaft 46 for sliding 60 movement toward and from the clutch member of the gear hub. The sleeve is formed with a circumferential groove 52 which receives rolls 53 on the upstanding members 54 of the bifurcated upper end of a rocker arm 55 which is fulcrumed 65 at its lower end on a shaft 56 fixed between brackets 57 on the frame base 20. The hub of the rocker arm has fast thereon an upstanding arm 58 equipped with a roll 59 which is operatively fitted in the peripheral race 60 of a cam 61 fast 70 on a shaft 63 parallel with the drive shaft. The shaft 63 is located medially of the base 20 and has its bearings in stands 64 on the base. (See Figs. 4 and 6.)

The cam shaft 63 is driven in timed relation to 75 the drive shaft 46 through a suitably-disposed

train of reducing gears between the two shafts, the gear train shown comprising a small gear 65 on the drive shaft in mesh with a larger gear 66 on a lower shaft 67 parallel with the drive shaft; a small gear 68 on the shaft 67 in mesh with a larger gear 69 on an adjacent parallel shaft 70, and a small gear 71 on the shaft 70 in mesh with a larger gear 72 on the shaft 63. (See Figs. 4, 5 and 6.) The ratio of the gears in the present instance is such that the cam shaft 63 makes one 10 rotation to twenty-six rotations of the drive shaft. The contour of the race 60 of the cam 61 is such that the clutch actuating arms 55, 58 are periodically moved to effect the sliding engagement of the sleeve clutch 50 with the gear clutch 49 15 and maintain the clutching action for a half rotation of the cam 61, and then to effect the disengaging relation of the clutches and maintain such relative position thereof during the succeeding 20 half rotation of the cam.

From the foregoing it will be seen that when the bevel gear 45 is clutched to the drive shaft 46 the upper cam shaft 38 makes thirteen rotations to each half rotation of the lower cam shaft 63 and then rests during the succeeding half rotation of the shaft 63. During the rotational period of the upper cam shaft 38 twenty-five books are transferred from each of the book troughs 24 to the adjacent assembly chamber 27, and during the idle period of such cam shaft the books are 30 transferred from the two chambers to an upper level where they are uniformly arranged in close parallel relation and then efficiently packed in an underlying carton (C), as will hereinafter appear.

The acting end of each of the book ejectors 28 is of sufficient width to engage two opposing books at the discharge end of the adjacent trough, and hence during each inward stroke of the ejector the two opposing leading books are simultaneously pushed from the trough into the adjacent 40 assembly chamber 27.

When each of the ejectors 28 has made twelve reciprocations, and therefore transferred twenty-four books to the adjacent assembly chamber, a 45 single leading book is pushed from the trough into the chamber, thus completing the row of twenty-five assembled books. To this end mechanism is provided to push the leading book in the trough slightly rearward so that it alone will be 50 in the path of the acting end of the ejector. The mechanism illustrated for this purpose comprises a horizontally reciprocative rod 73 whereof the free end is seated in the perforated outer 55 end wall 26 of the trough to be movable against the opposing face of the leading book which is seated in the path of the ejector 28. The outer end of the rod 73 is pivotally connected to the top of an upstanding arm 74 fast on a transverse rock-shaft 75 which has its bearings in the outer 60 ends of the frame standards. The arms for the two rods are fixed at the respective ends of the shaft 75. Fast on this shaft is a depending arm 76 having at its lower end a roll 77 which is normally held by means of a suitably disposed spring 78 against the flat face of a cam 79 on the lower cam shaft 63 previously described.

In this face of the cam 79 is a suitably-located socket 80 which reaches the roll 77 immediately upon the delivery of twenty-four books to each of the assembly chambers, whereupon the roll is caused to enter the socket by the retractive action of the spring 78 on the depending lever arm 76. Consequently this arm is swung slightly outward and the rocker shaft 75 is partially turned clock- 70 75

wise, thus moving the arms 74 and their respective rods 73 inward to such extent that the free end of each of the rods projects into the adjacent trough a distance equal to the width of a match book. (See Figs. 1, 2, 3, 4 and 8.)

When the rods 73 are thus inwardly projected, the ejectors 28 move inward and force the opposing single books into the respective assembly chambers; it being noted that the bifurcated acting portion of each ejector embraces the inwardly projecting end of the adjacent rod. In the next succeeding backward strokes of the respective ejectors, the bevel gear 45 is unclutched from the drive shaft 46, thus temporarily stopping the upper cam shaft 38 and therewith the operation of the ejectors; and when the socket 80 in the face of the cam 79 escapes the roll 77 the arms 74 and 76 are actuated by the opposing cam face to retract the respective rods 73 to their original outward positions and therein hold them during a complete rotation of the shaft 63, whereupon the socket will again receive the roll.

The floors of the assembly chambers 27 are at the same level as the floors of the adjacent book troughs so as to receive and support the lower ends of the match books as they are transferred by the ejectors from the troughs to the chambers, which floors are constituted by the heads 81 of oppositely swinging T-arms 82 when the latter are in downward position, as will be hereinafter described. The ends of the chambers are formed by the lower vertical portions of the two spaced parallel walls 83 of a bridge structure which is bolted to the respective frame standards, the space between the walls substantially corresponding in length with that of a row of twenty-five match books.

The bridge walls 83 are rounded at their ends, as at 84, and have rectangular openings 85 in their body portions. The inner side of each wall is formed or otherwise provided with curved ribs 86 adjacent to and concentric with the respective ends of the wall, each of which ribs extends through an arc of about 90°. The ribs of one wall correspond in form with the adjacent ribs of the other wall, and are edgewise spaced to provide between the walls two oppositely curved centrally slotted bridge tracks which rise from the respective assembly chambers and terminate at a horizontal level adjacent the tops of the vertical sides of the openings 85, thus affording a throat 87 between the upper ends of the two tracks. The throat is provided with a movable barrier, comprising in the present instance a pair of normally-closed swinging doors 88 which are hinged at their outer ends, as at 89, to and between the side walls 83 of the bridge structure. The doors are maintained yieldingly in horizontal or closing position across the throat by suitable torsional springs 90 which are secured to the pintles of the doors and to the adjacent bridge walls (see Figs. 3, 5, 8 and 9).

The lower portions of the tracks 86 are positioned to afford end abutments and horizontal guides for the match books as and when the books are transferred to the respective assembly chambers by the reciprocating bifurcated ejectors 28.

Mechanism is provided to maintain the match books (B) in upright position within each of the assembly chambers and advance the books therewith as the books are being progressively assembled in a row in the chamber. In the present instance this mechanism includes two opposed horizontally reciprocative rods 91 and 92 which are guided in perforations in the respective end

walls of each of the assembly chambers. The rod 91 is seated in the end wall at the receiving end of the chamber and is reciprocative with a stroke equal to the width of two books seated in the assembly chamber, thereby bearing against the opposing books in succession and pushing them bodily along the chamber as rapidly as they are received thereby. The rods 91 for the respective chambers may be termed "push rods".

The means illustrated for reciprocating the two push rods 91 in timed relation to the respective ejectors 28 comprises a pair of spaced counterpart cams 93 fast on the upper cam shaft 38. Horizontal plungers 94, which are slidably mounted in one of the upper cross-bars 22, are held with their inner ends yieldingly in contact with the respective cams 93 by means of suitably-disposed springs 95. The outer ends of these plungers are pivotally connected, as at 96, with the lower arms of a pair of vertical rock levers 97 which are fulcrumed, at 98, on the respective frame standards, and the upper ends of the levers are pivotally connected, in turn, with the respective push rods 91.

The rod 92 is seated in the bridge wall 25 at the remote end of the assembly chamber, and is gradually moved along and substantially throughout the length of the chamber. The free or acting end of the rod 92 is initially positioned adjacent the receiving end of the chamber to afford a back support for the first inserted pair of books, and as these books and the succeeding books are advanced by the rod 91, the rod 92 is gradually retracted in a manner to support the accumulating books upright and in close lateral relation within the chamber until the row has been completed. The rods 92 for the two chambers may be termed "backer rods".

The means illustrated for actuating the two backer rods 92 in timed relation to the respective ejectors 28 comprises a cam 99 fast on the adjacent end of the lower cam shaft 63, the race 100 of the cam having a dwell portion 101 extending about one-half of its circumference and oppositely-inclined acting portions 102 communicating with the respective ends of the dwell portion and converging to a short dwell portion 103.

Operatively fitted in the race 100 of the cam 99 is a roll 104 on the lower end of a depending arm 105 which is fast on a transverse rocker-shaft 106 having its bearings in rearward extensions 107 of the frame standards. This shaft 106 has secured thereto a pair of spaced upstanding arms 108 whereof the upper ends are pivotally connected by links 109 to the outer ends of the respective backer rods 92. Hence during the rotation of the cam 99 the two backer rods are simultaneously actuated and controlled, that it to say, when the respective assembly chambers have received their full quota of match books, the backer rods are fully retracted by the engagement of the roll 104 with the dwell portion 101 of the cam race, which condition of the rods obtains during a half rotation of the cam. Immediately thereafter the outwardly inclined portion 102 of the cam race receives the roll 104 and retracts it and its arm 105 during substantially a quarter rotation of the cam, thus gradually advancing the backer rods within the assembly chambers until the free ends of the rods are adjacent the paths 70 of the respective ejectors 28 and in position to serve as back supports for the first pairs of match books entered in the respective chambers. Thereupon the roll 104 rides on the short dwell portion 103 at the apex of the inclined portions of 75

the cam race and the backer rods are at rest, during which interval the first books are transferred by the ejectors 28 from the troughs to the respective chambers. The following inclined portion 102 of the cam race then receives the roll 104 which together with its arm is swung inward during a quarter rotation of the cam 99, thus gradually retracting the two backer rods 91 in timed relation to the entry of the succeeding books in the assembly chambers. At the completion of the cycle of the cam 99 the dwell portion 101 of the cam race 100 again receives the roll 104 of the rocker-arm 105, and so on during the operation of the machine the periodic inward and outward movements and dwells of the backer rods are effected.

The relation of the race 100 of the cam 99 to that of the clutch control cam 61, hereinbefore described, is such that when the clutch sleeve 51 is actuated to release from the drive shaft 46 the bevel gear 45 which is included in the transmission gearing for the upper cam shaft 38, the dwell portion 101 of the cam 99 engages the roll 104 of the rocker arm 105, and therefore the operation of the mechanism for transferring the books from the troughs to the assembly chambers, together with that of the mechanism for actuating the pusher rods 91 at the receiving ends of the chambers, is suspended during the inactive intervals of the retracted backer rods 92 at the opposite ends of the chambers.

In each of these inactive intervals the two rows of assembled books are bodily lifted from the respective chambers 27 and swung upward and toward each other upon the respective tracks 86 by actuation of the oscillatory T-arms 82 hereinbefore referred to. In this upward movement of the T-arms the two rows of books are swung thereby through opposite arcs of 90° respectively, thus partially turning the rows and compactly positioning them upon the doors 88 for the throat 87 at the upper ends of the tracks, and with the books of the respective rows in close end to end relation preparatory to their delivery as a unit to a carton located beneath the throat, as will presently appear.

As illustrated the shanks of the T-arms 82 are fast on a pair of spaced parallel rocker-shafts 110 having their axes coincident with the centers from which the respective trackways are described. These shanks extend radially and freely through the slots between the tracks, and the heads 81 of the arms overlie and travel in proximity to the adjacent tracks during the swinging motion of the T-arms.

The shafts 110 have their bearings in the walls of the bridge structure and in brackets 111 secured to the frame standards. These shafts are provided, adjacent the brackets, with outwardly extending crank arms 112 which are pivotally connected, as at 113, to the upper ends of two rods 114 which depend adjacent the machine base 20 and are shaped to overlap at their lower extremities directly below the axis of the lower cam shaft 63. The overlapping ends are jointed together and to the free end of a horizontal rock-arm 115 by a pivot pin 116; the opposite end of the rock arm being pivoted, as at 117, to one of the frame standards. The pivot pin 116 carries a roll 118 which is operatively fitted in a suitable cam race 119 in the face of the cam 61 on the shaft 63, the contour of the race being such that during the rotation of the cam 61 the roll 118 and therewith the rods 114 are periodically raised and lowered in a manner to

oscillate the shafts 110, and their respective T-arm. The shafts 110 are actuated and controlled immediately upon the complete assembly of the rows of books in the respective chambers 27 and while the book ejectors 28 and the pusher and backer rods 91 and 92, respectively, are at rest.

As an efficient means to bar the entry of books of the respective rows into the slots of the curved trackways of the bridge structure, not only when the books are being entered in and moved along the assembly chambers 27, but also while the rows are being swung upward to position them above the discharge throat 87 of the structure, a resilient guard blade 120 is affixed at one end to the hub of each of the T-arms 82, so that normally the outer or free end of the blade extends slightly in advance of the radial acting face of the head 81. This blade end is positioned to travel freely in the slot with the extremity of the blade flush with the upper face of the track. Preferably a reinforcing leaf spring 121 is secured at its lower end to the base of the blade 120 and to the adjacent hub so as to exert pressure against the inner face of the guard blade. (See Figs. 8 and 9).

By the construction just described it will be seen that the spaced free ends of the guard blades 120 serve to bar the accidental entry in the respective slots of any of the books situated at the mouths of the slots, not only during the assembly of the books in the respective chambers, but also during the upward travel of the books between the walls of the bridge structure. It will also be seen that as the T-arms approach their vertical or upright condition at the upper ends of the slots, the upper portions of the resilient guard blades bear against the opposed hinged members of the throat doors 88 and that such blades, therefore, by their inherent elasticity, permit the T-arms to swing to positions with the acting radial faces of the heads 81 in close relation to the doors. This done, the T-arms, together with the guard springs, are retracted from the doors, and permitted to assume their relative downward positions in the bridge structure.

As an efficient means to position the two rows of books uniformly and in close parallel relation when they have been placed upon the closed throat doors, preparatory to the delivery of the associated books through the throat to an underlying carton or other appropriate commercial container, a pair of elongated presser members are mounted and arranged for swinging movement toward and from the respective sides of the throat in timed relation to the T-arms, so as yieldingly to embrace the two rows of books when they have been moved to and upon the throat doors by the T-arms.

In the construction illustrated each of the presser members comprises a plate 122 having an upstanding acting portion 123 at its inner end, and a pair of pivot receiving lugs 124 at its outer end, which plate is approximately as wide as the space between the inner walls of the bridge structure so as to be freely movable therebetween in respect to the curved book supporting tracks. The lugs are pivoted, as at 125, to the lower end of a depending arm 126 which is loose on a rock shaft 127 journaled in spaced upright members 128 on the adjacent frame standard. Fast on the shaft 127 adjacent the hub of the arm 126, is a depending actuating foot 129 having a lateral toe 130 which lies in contact

with the inner edge of the arm 126. A collar 131 fast on shaft 127 serves to maintain the arm 126 in proximity to the hub of the actuating foot 129. (See Figs. 1, 2, 6, 7 and 9).

5 Correspondingly mounted depending arms 126 for the respective presser members are employed, the actuating feet 129 for the respective arms being oppositely disposed, as shown. These arms 126 are connected by a tension spring 132 which 10 maintains them yieldingly in contact with the toes 130 of the respective feet 129.

The inner or acting ends of the presser members are provided with projections or studs 230 which ride upon and are supported by the upper 15 edges of the bridge walls 83 during the reciprocation of such members toward and from each other. These edges comprise horizontal portions 231 which support the studs to maintain the respective presser members with their acting ends 20 123 in the plane of the books above the throat, and also comprise suitably-disposed raised cam portions 232 which lift the studs and the presser members to position the acting ends of the latter above the paths of the books on the trackways 25 as and when the presser members approach and reach the limits of their outward strokes, as hereinafter described.

The two rock shafts 127 have affixed thereto the outer ends of inwardly extending arms 133, 30 respectively, whereof the inner ends are provided with meshing gear sectors 134, and hence when one of the shafts 127 is partially turned the companion shaft is similarly turned, but in an opposite direction. Fast on one of the shafts 127 35 is the inner end of an outwardly extending arm 135 which is pivotally connected by a link 136 with a rocker arm 137 extending from a lower transverse shaft 138 journaled in bearings in the frame standards. On this shaft 138 is secured an arm 139 having a lateral roll 140 which is 40 operatively fitted in a cam race 141 formed in the outer face of the gear 72 which is fast on the lower cam shaft 63.

As shown, the cam race 141 comprises a concentric or dwell portion 142 interrupted by a suitably disposed actuating depression 143 which effects the periodical raising and lowering of the rocker-arm 139 in timed relation to the oscillating T-arm to produce the periodic rocking of the shaft 127 to which the arm 135 is connected, which movement is transmitted, in turn, to the other rock-shaft 127 through the gear connected arms 133.

In the extended interval when the concentric portion 142 of the cam race 141 is engaged with the roll 140 the arm 139 is maintained in its raised position to retract the actuating feet 129 and permit the arms 126 through their spring connection 132 to move, the presser members 45 yieldingly toward each other; and in the relatively short interval when the depression 143 is passing the roll 140 the rocker arm 139 is lowered and raised by the retractive force of the spring 132 through the connections between the upper rock-shafts and the lower rock-shaft.

When the roll 140 is in the depression and the rock arm 139 is lowered, the actuating feet 129 and the opposing arms 126 with their pivoted presser members are in outer positions with the 50 projections or studs 230 resting on the cam portions 232 of the bridge structure, thus supporting the presser members above the paths of the T-arms and the books during the succeeding upward and return strokes of the T-arms. The 55 depression receives the roll 140 until the two 75

rows of books have been swung upward and placed upon the throat doors 88 by the T-arms, whereupon, as these arms swing backward, the depression recedes from, and the concentric portion 142 of the cam race co-acts with the roll, thus raising the rock arm 139 and effecting the outward movement of the actuating feet 129 to permit the spring to retract the arms 126 and their respective presser members. In the initial inward movements of these presser members their 10 studs 230 pass from the cam portions 232 to the lower horizontal portions 231 of the bridge walls, and in consequence the presser members drop into the horizontal plane of the books previously 15 positioned on the doors, so that in the continuance of their inward movements, said members bear squarely, yet yieldingly, against the opposing rows of books and centrally align them above the bridge throat. In the return movements of the 20 presser members as they approach their outer limits, such members are raised by the passage of their projections or studs 230 on the respective cam portions 232 of the bridge walls.

While the presser members are embracing the associated books the latter are depressed as a 25 unit to open the doors and pass thence through the throat 87 into a suitably positioned carton, as will presently appear. The rock-arm 139 is held in raised position by the concentric portion 142 of the cam race during each succeeding downward and upward stroke of the T-arms, and also in the intermediate interval when the arms are 30 in down position and the match books are being transferred to and arranged in the respective assembly chambers.

The means herein illustrated for moving the associated rows of books through the bridge throat, against the resilient action of the doors 88, comprises a vertically reciprocative plunger 144 which is guided in a bracket structure 145 40 secured to one of the frame standards. The lower acting surface of the plunger, which normally overlies the throat 87 in a plane above that of the associated rows of books, corresponds in dimensions with the opposing area of the 45 books embraced by the parallel acting portions 123 of the presser members. The upper end of this plunger is pivotally connected by a link 146 to the inner ends of a pair of inwardly-extending arms 147 which are affixed at their outer ends to 50 the respective rock-shafts 127. Hence during the oscillatory motion of the shafts 127, as the depression 143 of the cam race 141 receives and 55 recedes from the roll 140 of the rock-arm 139, the plunger 144 is depressed and raised respectively. In its yieldable down stroke the plunger evenly presses the underlying books upon the doors 88 of the bridge throat in a manner to swing the doors downward and laterally outward, thereby forcing the books uniformly through the 60 throat and into a properly positioned carton, as will now be described. (See Figs. 1, 2, 3, 5, 6 and 7.)

A vertically-reciprocative carriage constituting a carton supporting and feeding structure extends longitudinally of the machine directly below the bridge throat. This structure comprises a substantial bar 148 which has up-turned bifurcated end extensions 149 and is secured to a pair of spaced vertical rods 150 which are slidably fitted in the cross-bars 22 of the main frame. These rods support at their upper ends a horizontal open-end trough 151 which extends freely through the openings 85 in the bridge-walls. The lower ends of the rods 150 are connected 75

by a cross-head 152, the extremities of which are provided with rolls 153 fitted in corresponding cam races 154, one of which is formed in the inner face of the gear 72 and the other in the inner face of the cam 61 on the lower cam shaft 63, which races are of such formation as to effect the raising and lowering of the rods 150 and their appurtenances in timed relation to the operation of the plunger 144.

10   Journaled in the end extensions of the bar 148 are two parallel cross shafts 155, 156, respectively. Fast on these shafts are sprocket wheels 157 about which pass a pair of intermittently movable spaced conveyor chains 158, whereof the upper runs 159 travel in parallel guideways 160 extending along the bottom of the trough 151. These chains are provided on their outer faces with regularly spaced lugs or projections 260 which are arranged in pairs to abut against each successive carton (C) imposed, mouth up, upon the upper runs of the chains, at one end of the trough, and then to advance the carton directly to and beneath the bridge throat in a position to receive the associated books as they are depressed by the plunger 144.

In the present instance the shaft 155 has fast thereon a ratchet wheel 161 with the teeth of which co-acts a spring-pressed pawl 162 pivoted on a rock-arm 163 loose on the shaft 155. This 30 arm 163 is pivotally connected by means of an outwardly extending link 164 with the upstanding arm 165 of a lever which is fulcrumed on a transverse shaft 166 fixed in brackets 167 on the adjacent ends of the frame standards. The 35 depending arm 168 of the lever is provided with a roll 169 which is operatively fitted in a race 170 formed in the cam 79 on the lower cam shaft 63, which race is of such formation in relation to the cam races 154 of the gear 72 and cam 61, respectively, that when the carton-supporting 40 structure is lowered the lower lever arm 168 is swung outward, thereby moving the upper arm 165 and the link 164 inward and effecting the actuation of the pawl 162 to advance the ratchet 45 wheel a predetermined distance; and that when the structure is lowered the pawl is idly retracted on the teeth of the ratchet wheel and is then maintained at rest until the next succeeding upward stroke of the structure. Thereupon the 50 pawl is actuated to advance the ratchet wheel another step, and so on at predetermined intervals. In each step of the ratchet wheel the shaft 155 and its sprocket wheels 157 are partially turned in a manner to impel the chains 159 along 55 the trough 151 a sufficient distance to position the leading carton under the throat of the bridge structure so that the throat doors 88 can be swung into vertical or fully-open position within and against the opposing inner side walls of the carton. (See Fig. 7).

The means illustrated for supplying the cartons, in succession to the receiving end of the trough and in proper position thereon for engagement by the advancing lugs 260 of the conveyor chains, is as follows:

172 designates a carton-supply trough located a suitable height above and parallel with the feed trough 151 and terminating in a curved chute 173 which leads to a point adjacent the receiving 70 end of the latter trough, so that cartons placed upside down in the trough 172 and advanced into the upper end of the chute will gravitate through an arc of substantially 90°, thus partially turning the cartons to permit their deposition, open side 75 up, on the intermittently-moving conveyor chains

151. The cartons, manually placed end to end in the trough 172, are fed therealong by a pair of feed belts 174 whereof the upper runs travel on the bottom of such trough. These belts pass about pulleys 175, the shafts 176 of which are 5 journaled in bearing brackets 177 at the respective ends of the supply trough. The shaft at the discharge end of the trough has fast thereon a pulley 178 about which passes a belt 179 which is guided by a suitably disposed pulley 180 at 10 one side of the chute and thence trained to and about a pulley 181 on the driven shaft 70 adjacent the lower cam shaft 63. Thus motion is transmitted from the shaft 70 to the pulley 178 in a manner continuously to impel the feed belts 15 174 and advance the superposed cartons in succession to the delivery chute.

To ensure the orderly delivery of the descending cartons to the conveyer chains 158 of the trough 151, so that each succeeding carton discharged from the chute will be properly positioned on the chains to be engaged by the approaching lugs 260, a trip device is constructed and arranged to swing periodically into and from the leading carton in the chute, and thereby temporarily arrest and then release the carton. (See Figs. 1, 5 and 6).

This device comprises a light curved blade 182 one end of which is secured to an arm 183 fast on a transverse rock shaft 184 journaled in the 30 frame standards adjacent the chute, while the other or free end of the blade curves outwardly and upwardly for movement into the interior of the delivery portion of the chute. Fast on one end of the rock-shaft is a crank arm 185 which is pivotally connected with the upper end of a depending rod 186, the lower end of which is provided with an eye or collar 187 loose on the adjacent shaft 156 of the reciprocating carton supporting and feeding structure. Hence during the downward movement of this structure the rod 186 is lowered and the blade 182 is swung to position its free end within the leading carton in the chute and thereby temporarily bar its egress, as seen in Figs. 1 and 5, and in the upward movement of the structure said rod is raised and the blade 182 is swung out from the carton so as to permit the descent of the carton to an inclined position with its leading end resting on the chains and its rearward end supported on the lower end 45 of the chute 173, as shown in Fig. 5.

In the succeeding downward movement of the reciprocative structure the chains are advanced one step by the co-operation of the pawl and ratchet devices, thereby advancing the inclined 55 carton from the chute and permitting it to drop flatwise in the trough and upon the chains in the path of the approaching lugs 260 on the latter. At the same time the leading carton in the trough 92 is impelled by the moving chains to a 60 position directly beneath the bridge throat, and therefore in the next succeeding upward stroke of the structure such leading carton is in position to receive the associated rows of books and the downwardly swung doors 88 as and when such 65 books are forced through the throat by the descending plunger 144, as previously described. This done, the reciprocative structure again descends, the doors 88 swing upward to close the 70 throat, and the chains are moved another step to advance the filled carton and position another empty carton beneath the throat, preparatory to the next succeeding ascent of the reciprocative structure; and so on.

It is to be understood that my invention is 75

not limited to the particular exemplifying form of embodiment herein disclosed, as the mechanisms may be variously modified within the principle of the invention and the scope of the 5 appended claims.

I claim—

1. In a machine for packing flat packets and the like, the combination of two elongated assembly chambers arranged in spaced parallel relation, a trackway connecting said chambers and having a throat therebetween, a barrier for said throat, means for progressively supplying a predetermined number of articles to the respective chambers, and means for moving the two rows of articles toward each other along the trackway and arranging them in juxtaposition upon the barrier.
2. In a machine for packing flat packets and the like, the combination of two elongated assembly chambers arranged in spaced parallel relation, a trackway connecting said chambers and having a throat therebetween, a barrier for said throat, means for progressively supplying a predetermined number of articles to the respective chambers, and means including two oppositely-moving members for moving the two rows of articles toward each other along the trackway and arranging them in juxtaposition upon the barrier.
3. In a machine for packing flat packets and the like, the combination of two elongated assembly chambers arranged in spaced parallel relation, an arched trackway connecting said chambers and having a throat therebetween, a barrier for said throat, means for progressively supplying a predetermined number of articles to the respective chambers, and means including two oppositely-moving oscillating members for moving the two rows of articles toward each other along the trackway and arranging them in juxtaposition upon the barrier.
4. In a machine for packing flat packets and the like, the combination of two elongated assembly chambers arranged in spaced parallel relation, a trackway connecting said chambers and having a throat therebetween, a barrier for said throat, means for progressively supplying a predetermined number of articles to the respective chambers, means for moving the two rows of articles toward each other along the trackway and arranging them in juxtaposition upon the barrier, means for feeding cartons successively beneath said throat, and means for passing the two rows through the throat against the action of the barrier and into an underlying carton.
5. In a machine for packing flat packets and the like, the combination of two elongated assembly chambers arranged in spaced parallel relation, a trackway connecting said chambers and having a throat therebetween, a barrier for said throat, means for progressively supplying a predetermined number of articles to the respective chambers, means for moving the two rows of articles toward each other along the trackway and arranging them in juxtaposition upon the barrier, means for then pressing the two rows into close parallel relation, means for feeding cartons successively beneath said throat, and means for passing the two rows through the throat and into an underlying carton.
6. In a machine for packing flat packets and the like, the combination with means for supporting a succession of advancing articles, and an assembly chamber adjacent thereto, of transfer means for removing an aggregate uneven number of said articles and arranging them in a row in

said chamber, said means including an element which transfers successive even numbers of articles to the chamber until the row approaches completion and then transfers an uneven number thereof to the chamber to complete the row.

7. In a machine for packing flat packets and the like, the combination with means for supporting a succession of advancing articles, and an assembly chamber adjacent thereto, of transfer means for removing an aggregate uneven number of said articles and arranging them in a row in said chamber, said means including an element which transfers successive even numbers of articles to the chamber until the row approaches completion and then transfers an uneven number thereof to the chamber to complete the row, and including also an element that successively advances the articles along the chamber a distance equal to the width of each succeeding number of articles introduced thereto.

8. In a machine for packing flat packets and the like, the combination with means for supporting a succession of advancing articles, and an assembly chamber adjacent thereto, of transfer means for removing an aggregate uneven number of said articles and arranging them in a row in said chamber, said means including an element which transfers successive even numbers of articles to the chamber until the row approaches completion and then transfers an uneven number thereof to the chamber to complete the row, and including also an element that successively advances the articles along the chamber a distance equal to the width of each succeeding number of articles introduced thereto, a backer element for the articles within the chamber, and means for gradually retracting said backer element in timed relation to the delivery of the articles in the chamber until the row has been completed, and then returning said backer element to its original position.

9. In a machine for packing flat packets and the like, the combination of means for supporting a succession of advancing articles, an abutment member, means for periodically projecting said member into or retracting it from the path of the leading article at predetermined intervals, an assembly chamber adjacent said article supporting means, an ejector reciprocative transversely of the delivery end of said supporting means, the acting portion of said ejector being of a width to bear against a definite plurality of the leading articles and transfer them into the assembly chamber during each succeeding active stroke of the ejector when the abutment member is retracted, and for engaging a lesser number, at least one, of the articles when the abutment is inwardly projected.

10. In a machine for packing flat packets and the like, the combination of means for supporting a succession of advancing articles, an abutment member, means for periodically projecting said member into or retracting it from the path of the leading article at predetermined intervals, an assembly chamber adjacent said article supporting means, an ejector reciprocative transversely of the delivery end of said supporting means, the acting portion of said ejector being of a width to bear against a definite plurality of the leading articles and transfer them into the assembly chamber during each succeeding active stroke of the ejector when the abutment member is retracted, and for engaging a lesser number, at least one, of the articles when the abutment is inwardly projected, means for moving said articles along

- the chamber as they are entered therein until a predetermined number of articles have been assembled in a row, and means for bodily removing the row broadside from the chamber.
- 5 11. In a machine for packing flat packets and the like, the combination of means for supporting a succession of advancing articles, an abutment member, means for periodically projecting said member into or retracting it from the path of the leading article at predetermined intervals, an assembly chamber adjacent said article-supporting means, an ejector reciprocatively transversely of the delivery end of said supporting means, the acting portion of said ejector constructed to bear against a definite plurality of the leading articles and transfer them into the assembly chamber during each succeeding active stroke of the ejector when the abutment member is retracted, and for engaging a lesser number, 10 at least one, of the articles when the abutment member is inwardly projected, means for intermittently moving the articles along the assembling chamber as they are successively delivered therein, a back support for the articles within 15 said chamber, and means for gradually retracting said support in timed relation to the delivery of the articles in the chamber and for returning said back support to its original inward position within the assembling chamber when a predetermined number of articles have been assembled 20 in a row therein.
12. In a machine for packing flat packets and the like, the combination of means for supporting a succession of advancing articles, an abutment member, means for periodically projecting said member into or retracting it from the path of the leading article at predetermined intervals, an assembly chamber adjacent said article-supporting means, an ejector reciprocatively transversely of the delivery end of said supporting means, the acting portion of said ejector constructed to bear against a definite plurality of the leading articles and transfer them into the assembly chamber during each succeeding active 25 stroke of the ejector when the abutment member is retracted, and for engaging a lesser number, at least one, of the articles when the abutment member is inwardly projected, means for intermittently moving the articles along the assembling chamber as they are successively delivered therein, a back support for the articles within said chamber, means for gradually retracting said support in timed relation to the delivery of the articles 30 in the chamber and for returning said back support to its original inward position within the assembling chamber when a predetermined number of articles have been assembled in a row 35 therein, and means for bodily removing the row broadside from the chamber.
- 60 13. In a machine for packing flat packets and the like, the combination of two elongated assembly chambers arranged in spaced parallel relation, means for assembling the articles in the respective chambers to produce therein two corresponding rows of articles, an article-support between the two chambers, and means for moving the two rows of articles broadside toward each other and arranging them in juxtaposition upon the said support.
- 70 14. In a machine for packing flat packets and the like, the combination of two elongated assembly chambers arranged in spaced parallel relation, means for assembling the articles in the respective chambers to produce therein two corresponding rows of articles, an article-support be-
- tween the two chambers, and means for moving the two rows of articles broadside toward each other through an arc of about 90° and arranging them in juxtaposition upon the said support.
15. In a machine for packing flat packets and the like, the combination of two elongated assembly chambers arranged in spaced parallel relation, means for assembling the articles in the respective chambers to produce therein two corresponding rows of articles, an elevated support 10 between the two chambers, and oscillating members movable in vertical arcs between the respective chambers and the support and operative to swing the two rows of articles broadside toward each other and in juxtaposition upon the said support.
16. In a machine for packing flat packets and the like, the combination of two elongated assembly chambers arranged in spaced relation, slotted arcuate trackways rising from said chamber to a 20 horizontal level intermediate the two chambers, a support for articles between the upper ends of the trackways, oscillatory members extending through the slots of the trackways and movable between the respective chambers and the support, and means for actuating said members to swing the two rows of articles broadside toward each other and in juxtaposition upon the said support.
17. In a machine for packing flat packets and the like, the combination of two elongated assembly chambers arranged in spaced relation, slotted arcuate trackways rising from said chamber to a horizontal level intermediate the two chambers, a support for articles between the upper ends of the trackways, oscillatory arms extending through the slots of the trackways and having pusher heads overlying said trackways and movable through arcs between the respective chambers and the elevated article support, means for actuating said arms to swing the two rows of articles broadside toward each other and in juxtaposition upon the said support, and resilient barrier blades carried by said arms and having their extremities freely entered in said slots and normally spaced 35 from the active surfaces of the heads of the respective oscillatory arms.
18. In a machine for packing flat packets and the like, the combination of a support, means for depositing rows of articles in juxtaposition upon said support, and means for transversely pushing said rows toward each other and in close parallel relation upon said support, said latter means comprising a pair of members having opposing parallel acting surfaces, pendant rock arms to 50 which said members are pivoted, and means for periodically swinging said arms and the presser elements toward and from the support.
19. In a machine for packing flat packets and the like, the combination of a support, means for depositing rows of articles in juxtaposition upon said support, and means for transversely pushing said rows toward and in close parallel relation with each other upon said support, said latter means comprising a pair of elements having opposing parallel acting surfaces, pendant rock arms to 55 which said elements are pivoted, means for yieldingly swinging said arms and the presser elements toward the support, and means for thereafter retracting the said arms and their presser elements.
20. In a machine for packing flat packets and the like, the combination of a support, means for depositing rows of articles in juxtaposition upon said support, means, including presser ele- 70

ments, for transversely pushing said rows toward each other and in close parallel relation upon said support, and means for raising and temporarily supporting the presser elements as they 5 travel backward.

21. In a machine for packing flat packets and the like, the combination of a support, means for depositing rows of articles in juxtaposition upon said support, and means for transversely 10 moving said rows toward each other and in close parallel relation upon said support, said latter means comprising a pair of complementary elements having parallel acting surfaces, pendant rock arms to which said elements are pivoted, 15 resilient means urging said arms toward each other, rocker members for spreading said arms against the action of the resilient means, and means for actuating said rocker members at predetermined intervals.

20 22. In a machine for packing flat packets and the like, the combination of a support having a discharge throat, a barrier for said throat, means whereby articles are orderly arranged upon said barrier, a carriage beneath said throat, 20 means for vertically-reciprocating said carriage, means mounted on and reciprocative with said carriage for feeding cartons successively under the throat when the carriage is in down position, and means whereby the said barrier is opened 25 30 and the articles thereon are moved through the throat and into the cartons when the carriage is in raised position, and whereby said barrier is closed when the carriage is lowered.

23. In a machine for packing flat packets and 35 the like, the combination of a support having a discharge throat, a barrier for said throat, means

for arranging articles in orderly position upon said barrier, a carriage beneath said throat, means for vertically reciprocating said carriage at predetermined intervals, an intermittently movable conveyer for a succession of cartons, 5 said conveyer being mounted on said carriage beneath and longitudinally of the throat, means for actuating said conveyer in the downstroke of the carriage to position a carton under the throat, and means for depressing the said articles and opening the throat when the carriage is in raised position.

24. In a machine for packing flat packets and the like, the combination of a support having a discharge throat, a barrier for said throat, means 15 for arranging articles in orderly position upon said barrier, a carriage beneath said throat, means for vertically reciprocating said carriage at predetermined intervals, an intermittently movable conveyer for a succession of cartons, 20 said conveyer being mounted on said carriage beneath and longitudinally of the throat, means for actuating said conveyer during the downstroke of the carriage to position a carton under the throat, means for depressing the said 25 articles and opening the throat when the carriage is in raised position, and means for supplying carton successively to the conveyer, said last-named means including a chute, a stop device movable into and from the path of each succeeding leading article in the chute, and operative connections whereby said stop device is actuated concurrently with the reciprocations of the carriage.

MICHAEL PARIDON. 35
